WIRES CONNECTER

Raymond N. Rowe, Plainville, Conn., assignor to
The Trumbull Electric Manufacturing Company, Plainville, Conn., a corporation of Connecticut

Application December 9, 1935, Serial No. 53,519

3 Claims. (Cl. 173—269)

The present invention relates to electrical connectors. In the production of connectors for commercial use it is desirable that the parts be few and the construction be simple and rugged.

5 One object of my invention is to produce a simplified and sturdy wire or cable clamp.

My invention also contemplates an improved electrical connector in which a cable or wire can be readily secured with a good electrical and 10 mechanical connection.

For economical manufacture and use, connectors should be capable of being easily assembled without the use of solder. My invention 15 embraces a device of this character. Another object is the design of a clamp with a minimum number of parts.

Still another object of the invention is to make a connector unit which can be handled and transported as a unit before use, without fear 20 of losing any of the parts.

These objects, and others, will be apparent 25 from the following description taken in connection with the accompanying drawing in which:

Fig. 1 is an end view of the connector without any cable.

Fig. 2 is a side view of the same.

Fig. 3 is a plan view of the same.

Fig. 4 is a drop perspective view of the parts of 30 the clamp.

Fig. 5 is a longitudinal sectional view showing a cable end clamped in place.

Fig. 6 is a view of the underside of the clamp.

The preferred form of wire or cable connector according to my invention includes a body 10 which may be of box-like form as shown. A 35 terminal foot 11 is made integral with one side of the body 10. This foot is riveted, bolted or otherwise secured to a switch, panel or other support.

40 At 12, in the body 10, is a recess for the cable 13 and for the clamp which holds the cable. The cable clamp includes the clamp plate 14 and the clamp screw 15. This screw is exteriorly threaded through one wall of the body 10.

45 At 16, in the body 10, is formed a V groove with inclined sides for the partial reception of a cable end. In the clamp plate 14, opposite the groove 16 when the parts are in operative position, is located a V groove 17 with inclined walls. This groove 17 has a roughened surface 50 or teeth as at 18 in order to grip the cable firmly.

For holding the parts loosely together a stem 19 is formed on the top of plate 14, the height 55 of the stem being such that the plate and stem

can be easily slid into the recess 12 when no cable is present and when the lower end of screw 15 is above the top of the recess. As soon as the nut is screwed down so that its inner end extends beyond the surface of the recess 12, 5 the stem 19 enters the recess 20 and the plate and stem are held within the body 10.

The recess 20 is made sufficiently larger than the stem 19 so that a limited amount of play between the nut and the plate is possible. Note 10 Fig. 5 in which the plate and stem are shown slightly tilted as they may be under some conditions.

By shaping the recess 20 into a hexagonal or other non-circular form, this recess serves the 15 double purpose of receiving the stem 19 and acting as a socket for a wrench or other tightening tool.

In the operation of this connector it is seen that the parts can all be assembled as a unit and carried as such from place to place simply by 20 sliding the clamping plate into the recess 12 and then screwing down the screw until the stem and screw hold the plate from sliding out of the recess. It should be clear that even though the parts are now assembled, considerable vertical 25 and tilting movement of the plate is possible.

The foot 11 can then be connected to the desired element and the bare end of cable 13 placed under the plate in the groove 16. The screw 15 is then tightened, compressing the cable 30 strands and, because of the inclined walls of the grooves 16 and 17, spreading the strands to a limited extent while they are being compressed. The friction due to the spreading brightens the 35 surfaces of the wires in the cable and produces a better possibility for electrical contact. The roughened surface 18 bites into the cable to improve both electrical and mechanical connection between the clamp and the cable. All of the 40 parts are preferably made of conductive material.

Because of the engagement of the stem 19 within the recess 20 it is impossible for the plate to be pulled out of the recess 12 by stresses on 45 the cable. In spite of this, the connection between the screw and the plate permits a tilting of the plate in any direction to compensate for irregularities in the thickness or position of the cable end.

As the clamp screw has a passage 20 through 50 it the stem of the clamp plate is accessible so as to permit a tool to be inserted to loosen the plate in case its gets wedged or stuck.

While I have illustrated and described one preferred form of electrical connector, it is ob- 55

vious that the principles involved could be embodied in other structures without departing from the spirit of this invention.

With this in mind, I claim:

- 5 1. A wire terminal having a cast metal body with a socket for receiving the end of a conductor, a clamping plate having a projecting stem and insertable into said socket from one end of the socket, said body having a screw-threaded 10 passage intersecting said socket, the diameter of the passage being approximately equal to the width of said socket and a clamp screw adjustable in said passage, said screw having a passage through it enough larger in diameter than 15 said stem to permit the clamp plate and its stem to tilt when the screw is tightened against the plate around the stem, said stem and plate being accessible through the passage in the screw, the stem of the plate extending part way 20 into the passage in the screw and leaving room above the stem for the reception of a wrench, said screw engaging the stem and holding the plate and its stem from accidental removal when the conductor is removed and the screw is 25 tightened.
2. An electrical connector including a rigid one-piece cast metal body having a wire-receiving recess therein and having an integral anchorage lug, a clamping plate freely movable within said recess, a stem integral with one side of said plate, the overall dimensions of said plate and stem being such that both plate and stem can be slidably inserted into said recess, a 30 clamping screw threadedly engaged in one wall 35 of said body and capable of being screwed to extend into said recess to clamp said plate, said screw having an aperture therein of materially larger diameter than said stem and adapted to surround said stem loosely when the screw extends into the recess, whereby the screw holds the stem and plate from sliding out of the recess while permitting sliding and tilting movement of said plate within said recess.

passage through said screw into which said stem loosely extends, a part at least of said recess being polygonal in cross section to accommodate an actuating wrench which wrench may engage against the end of the stem in the screw, said screw bearing on said plate around said stem, the sides of said recess between which the plate is moved being parallel and of such extent that when the bottom of the screw is adjacent the top of said recess and the recess is empty, the 10 clamp plate and stem may be inserted through an end of said recess and the stem inserted in the adjacent passage of the screw after which a conductor may be inserted in the body recess and said plate clamped on a conductor 15 by said screw.

3. An electrical connector including a rigid one-piece cast metal body having a wire-receiving recess therein and having an integral anchorage lug, a clamping plate freely movable within said recess, a stem integral with one side of said plate, the overall dimensions of said plate and stem being such that both plate and stem can be slidably inserted into said recess, a 20 clamping screw threadedly engaged in one wall 25 of said body and capable of being screwed to extend into said recess to clamp said plate, said screw having an aperture therein of materially larger diameter than said stem and adapted to surround said stem loosely when the screw extends into the recess, whereby the screw holds the stem and plate from sliding out of the recess while permitting sliding and tilting movement of said plate within said recess.
